CABLE STITCH KNITTING

Jack Fontaine, Cleveland, Ohio, assignor of
 32½/100 to Leonard Rapaport, Shaker Heights,
 Ohio

Application January 30, 1946, Serial No. 644,209

5 Claims. (Cl. 66—63)

1

If, in knitting, certain rows of stitches be inter-transposed with other rows whereby one such set is twisted across over the other, a rope-like or cable appearance is given, which is desirably ornamental. Such cable stitch knitting effect has been difficult to attain heretofore, by reason of its highly specialized character. In accordance with the present invention, however, such knitting effect may be attained very conveniently, and with relatively simple changes in equipment and operation of well-known knitting machinery. Thus, knitting machines of the link-and-link flat type may be readily converted and be operated to produce cable stitch fabrics.

To the accomplishment of the foregoing and related ends, the invention, then, comprises the features hereinafter fully described, and particularly pointed out in the claims, the following description and the annexed drawings setting forth in detail certain illustrative embodiments of the invention, these being indicative, however, of but a few of the various ways in which the principle of the invention may be employed.

In said annexed drawings:

Fig. 1 is a fragmentary plan view of the needle-plates of a flat knitting machine, equipped with special needles, and showing the first step toward the transposition of stitches to produce cable stitch knitting;

Figs. 2 and 3 are side view and plan view respectively of the special needle applied in the grooved needle-plates;

Fig. 4 is a side view of the jack which can be used to shift the needles;

Figs. 5, 6, 7, 8, 9 and 10 are plan views similar to Fig. 1, showing the further successive steps in effecting the transposition of stitches for the cable stitch knitting; and

Fig. 11 is a fragmentary plan view of an illustrative cable stitch product.

In a knitting machine of flat type, having needle-supports or needle-plates 2, 2', Fig. 1, these being mounted adjacent each other and having means for racking or relatively moving the plates as in known detail and which need not be shown here, the needle grooves 3 are provided with needles 4, which, as seen in Figs. 2 and 3, have the peculiarity of having hooks 5, 6, at the ends, but only one is provided with a closing member or latch 7. With such hooks in the needle grooves, and the yarn fed by the customary guides, stitch-loops are laid on the needle hooks. As illustrated in Fig. 1, there is one set of needles represented by a, f, on one plate, only

2

the two boundary needles being necessary to be shown, these forming the stitches as represented at a and f and the rest of the adjoining knitted fabric F, Fig. 11. And, between the groups of needles represented at a and f forming the ground-work of body of the knitted fabric is an intermediate group, represented by b, c, d, e, the needles here being on the opposite plate 2'. It will be understood that the precise number of this intermediate group may vary considerably, within practicable limits, dependent upon how many stitch rows it is desired to transpose into cable effect. Thus, the group of four stitch rows as involved in the transposing, may be taken as illustrative. With the stitch-loops set as in Fig. 1, next one plate is moved relatively in front of the other, or is racked, as it is sometimes termed, to a position as in Fig. 5, where the initially more remote stitch-loops, here b, c, are brought to a position adjacent the needle and loop f bounding the groundwork fabric as being formed on the opposite plate 2. The needles and stitch-loops b, c, are now opposite the empty grooves which are alongside the needle and stitch-loop f. At this juncture, the needle jacks 8 are moved by the co-action of cam grooves C on their projections 9, Fig. 4, such cams being on the order as known in these machines, and being in the cover plate which moves longitudinally of the needle-plate, and the needles and stitch loops b, c, are slid across and are picked up by the jacks of the other plate and are pulled into the grooves 3c, 3d, Fig. 5, the stitches sliding on the needles to the other hook end, the position now being that shown in Fig. 6. With another relative movement or racking movement, the needles and stitch loops d, e, are then brought back opposite the empty grooves 3d, 3e, alongside the needle and stitch-loop a. Again, the cams come into action and the jacks slide the needles, and the jacks on the other plate draw them back through the stitch-loops, to the position shown in Fig. 8, the yarn of the stitch rows d, e, being pulled over above that of the stitch rows b, c. With a lateral movement or racking, the plates are then returned relatively to the position in Fig. 9, and then the cams come into action and the jacks slide all of the transferred needles and stitch loops d, e, b, c, back onto plate 2'.

It will be noticed that in the sliding of the needles with respect to the stitch-loops, in the movement from one plate to the other, the latches 7 function only one way, and allow the stitches to be carried insofar as necessary, and then be

cast off. The knitting then proceeds through several courses of stitches, in number as determined by the particular proportions and pattern desired, and then with appropriate control, as by generally known pattern chain means, the twist effect may be repeated, and so on.

It will be noticed that with the equipment of special needles as afore-described, and the appropriate racking and transpositions, mechanism of the flat knitting type may be very conveniently operated to produce novel effects in cable stitch form and with greater or less elaborateness of design, as desired.

Other modes of applying the principle of the invention may be employed, change being made as regards the detail described, provided the features stated in any of the following claims, or the equivalent of such, be employed.

I therefore particularly point out and distinctly claim as my invention:

1. The method of knitting on link-and-link flat type knitting machines having grooved needle-plates and racking means, which comprises making cable stitches by providing in the grooves of the needle plates needles having an open hook at one end and a hook with closing member at the other end, forming a row of stitch-loops on the needle hooks on one plate in an intermediate group between spaced stitch-loops on oppositely directed hooks on the opposite plate, relatively moving some of the stitch loops and needles to position the initially more remote stitch-loops and needles of the said intermediate group near to one of said spaced stitch-loops and needles on the opposite plate and then sliding said relatively moved needles of the said intermediate group across to such opposite plate with the stitch-loops sliding along their needles to the hooks of the other end, relatively moving the rest of the stitch-loops and needles of said intermediate group near to the other of said stitch-loops and needles originally on the opposite plate, and sliding such other needles of the said intermediate group across to such opposite plate with the stitch-loops sliding along their needles to the hooks of the other end, then sliding all such transferred needles of the said intermediate group back to their original plate and bringing their stitch-loops onto the other end of the needles, knitting for several courses, and then repeating the foregoing steps.

2. A method of knitting on link-and-link flat type knitting machines having grooved needle-plates and racking means with needles having an open hook at one end and a hook and closing element at the other end, which comprises making cable stitches by forming a row of stitch-loops on needle hooks of one plate in an intermediate group between spaced stitch-loops on the opposite plate, racking to position the initially more remote stitch-loops and needles of the intermediate group near one of said spaced stitch-loops and needles on the opposite plate, and sliding some of the racked needles across to such opposite plate, racking to bring the rest of the stitch-loops and needles of said intermediate group to face the space yet left between said spaced stitch-loops, and sliding the needles across to such opposite plate, then sliding all transferred needles back to their original plate, knitting for several courses, and then repeating the foregoing steps.

3. A method of knitting on flat type knitting machines having two grooved needle-plates and needles with one open hook and one hook with a closing element and racking means, which comprises making cable stitches by forming a row of stitch-loops on needle hooks of needle-plate No. 1 in an intermediate group between spaced stitch-loops on the opposite plate No. 2, racking one needle-plate to position initially more remote stitch-loops and needles of the said intermediate group of needle-plate No. 1 near one of said spaced stitch-loops and needles on the needle-plate No. 2, and sliding the needles across to such needle-plate No. 2 whereby the stitch-loops slide each along its needle into open opposite end hooks of the same needle, racking to bring the remaining stitch-loops and needles of said intermediate group to a position facing the space yet left on needle-plate No. 2, and sliding the needles across to such needle-plate No. 2 whereby the stitch-loops slide each along its needle into opposite open end hooks of the same needle, then sliding all transferred and interchanged needles and stitch-loops back to their original plate, knitting for several courses, and then repeating the foregoing steps.

4. Cable stitch knitting with sets of differently directed needle hooks, comprising forming a plurality of stitch-loops on one set of hooks as an intermediate group between spaced stitch-loops formed on the other set of needle hooks, racking to bring the initially more remote stitch-loop of said intermediate group near to one of the said spaced other directed stitch-loops according to pattern and transferring such initially more remote stitch-loop into a hook of the other needle set, then racking to bring the remainder of the stitch-loops of said intermediate group to a position facing the space yet left between the said spaced stitch-loops and transferring same into such space, re-placing all transferred loops back to their original orientation, knitting a plurality of courses, and then repeating the aforesaid steps.

5. Knitting with sets of differently directed needle hooks, comprising knitting cable stitch effects by forming a plurality of intermediate stitch-loops on one set in position between spaced stitch-loops on the other set, relatively laterally moving said intermediate stitch-loops and transferring at least one therefrom over to a position in the other set, then reversely relatively laterally moving the remainder of the intermediate stitch-loops and transferring at least one to a position alongside a previously transferred stitch-loop, knitting a plurality of courses, and then repeating the aforesaid steps.

JACK FONTAINE.
